The ornamental design for a mailbox post topper, as shown and described.

DESCRIPTION

FIG. 1 is a top perspective view of a mailbox post topper, showing my new design;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines showing example address numbers on the mailbox post topper, and showing an example mailbox and mailbox post, illustrate example environmental structure, are not part of the design sought to be patented, and form no part of the claimed design.
